US00D954709S

(12) **United States Design Patent** (10) **Patent No.:** **US D954,709 S**
(45) **Date of Patent:** **** Jun. 14, 2022**

(54) **ELECTRONIC CONSOLE**

(71) Applicant: **Microsoft Corporation**, Redmond, WA (US)

(72) Inventors: **Carl J. Ledbetter**, Mercer Island, WA (US); **Nicolas A. Denhez**, Seattle, WA (US); **Bryan A. Sparks**, Sammamish, WA (US); **Brett D. Christie**, Seattle, WA (US); **Gregory Jones**, Seattle, WA (US); **Christopher H. Kujawski**, Seattle, WA (US)

(73) Assignee: **Microsoft Corporation**, Redmond, WA (US)

(**) Term: **15 Years**

(21) Appl. No.: **29/692,085**

(22) Filed: **May 22, 2019**

(51) **LOC (13) Cl.** **14-02**
(52) **U.S. Cl.**

USPC **D14/349**

(57) **CLAIM**

The ornamental design for an electronic console, as shown and described.

DESCRIPTION

FIG. 1 is an isometric view of an electronic console showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the encircled portion labeled as **8** in FIG. 1;

FIG. 9 is an enlarged view of the encircled portion labeled as **9** in FIG. 3;

FIG. 10 is an enlarged view of the encircled portion labeled as **10** in FIG. 6;

FIG. 11 is an enlarged view of the encircled portion labeled as **11** in FIG. 7; and,

FIG. 12 is a cross-sectional view taken through line **12-12** of FIG. 6, showing the concave upper region of the electronic console.

The even-length broken lines in FIGS. 1-3 and in FIGS. 5-12 illustrate portions of the electronic console that form no part of the claimed design. The uneven-length broken lines in FIGS. 1, 3, and 6-12, illustrating the enlarged detail views, are for annotative purposes and form no part thereof.

1 Claim, 10 Drawing Sheets
